ACCOUNTING MACHINE

Oscar J. Sundstrand, West Hartford, Conn., assignor to Underwood Elliott Fisher Company, New York, N. Y., a corporation of Delaware

Original application June 29, 1939, Serial No. 281,772. Divided and this application December 30, 1939, Serial No. 311,743

4 Claims. (Cl. 235—59)

This invention relates to accounting machines and more particularly to machines having column registers in which numbers are entered digit by digit and a crossfooter, or cross computing register arranged to be actuated to correspond with the actuation of the registers. The invention is shown as embodied in a typewriting and accounting machine of the Elliott-Fisher type.

In crossfooters of the usual construction employed in machines of the above type, the transfer mechanisms for the respective trains of accumulator wheels of the crossfooter are tripped in succession as said trains are actuated in succession by the master wheel of the crossfooter. This master wheel moves step by step across the several trains of the crossfooter to correspond with the movement of the master wheel which operates the column registers, across said registers. The transfer mechanisms remain in tripped position until the end of the register and crossfooter actuation and must be restored to operating positions before another accumulating operation of the crossfooter.

The primary object of the present invention is to provide accounting machines of the type in which numbers are entered digit by digit in the registers and crossfooters with novel and improved mechanism for resetting the transfer mechanism of the crossfooter by power.

With the above object in view, the invention consists in a transfer resetting mechanism for the crossfooter embodying the novel and improved features, constructions and combinations of parts hereinafter described and particularly pointed out in the claims, the advantages of which will be readily understood and appreciated by those skilled in the art.

The invention will be clearly understood from the accompanying drawings illustrating a machine embodying the invention in its preferred form and the following detailed description of the construction therein shown.

The present application constitutes a division of applicant's pending application Serial No. 281,772, filed June 29, 1939.

In the drawings:

Figure 1 is a view in vertical section of the machine and illustrating particularly the type bar operating mechanism and the mechanism for operating the registers or totalizers to enter the numerals from 3 to 9, inclusive.

Figure 2 is a view in rear elevation illustrating certain parts of the head or type carriage of the machine.

Figure 3 is a view in vertical section taken sub-

stantially in the line 3—3 of Figure 2 and illustrating particularly the totalizing mechanism of the cross computing register.

Figure 4 is a view in side elevation illustrating the driving motor and the driving connections between the motor and the toothed shafts for operating respectively the type bar mechanism and the totalizer mechanisms of the registers.

Figure 5 is a detail view in side elevation illustrating particularly the mechanism for resetting the carry devices of the cross computing register or cross totalizer.

Figure 6 is a view in front elevation illustrating certain parts of the mechanism shown in Figure 5.

Figure 7 is a detail sectional view taken substantially on the line 7—7 of Figure 5.

Figure 8 is a detail view in rear elevation, partly broken away and illustrating certain parts of the mechanism shown in Figure 5, and

Figure 9 is a view similar to Figure 8 illustrating certain of the parts in different positions.

The machine embodying the invention, as illustrated in the drawings, comprises a platen frame, one of the side rails of which is indicated at 2, a substantially flat platen 4 mounted for vertical movement in said frame, a line space frame, a portion of which is indicated at 6, mounted for forward and rearward movement on said platen frame, and mechanism for imparting line spacing movement to the line space frame at the end of each return movement of the carriage, all as shown and described in applicant's pending application referred to above.

Upon the line space frame is mounted a type carriage or head indicated as a whole at 20 upon which are supported the usual series of type bars each carrying one or more types for engaging the work sheets supported on the platen. The type bars are arranged to be operated by a power driven mechanism in the present machine, and this mechanism in part is carried by the carriage. The carriage also carries the usual series of keys forming the keyboard of the machine and controlling the coaction of the type bars with the power driven mechanism. The carriage also carries a master wheel by which the totalizers or registers are driven and mechanism for driving the master wheel differentially by power to set up or enter successively the various digits of a number step by step in a register.

The type carriage is mounted for movement forwardly and rearwardly with the line space frame and is also mounted for lateral movement on said frame in a right-hand direction to let-

ter space during a typing operation and for return movement in a left-hand direction to restore the carriage to position for starting the typing of a line. The carriage is provided with front and rear wheels or rollers arranged to engage respectively the front and rear rails of the line space frame of which the rollers engaging the rear rail 10 of said frame are indicated at 24. The carriage is acted upon by the usual metallic band 26 having one end attached to the carriage and connected with the usual spring drum 28 which tends yieldingly to move the carriage constantly in a right hand direction along the rails of the line space frame. The letter spacing movement of the carriage is controlled by the usual escapement mechanism indicated as a whole at 30.

The several type bars of the machine, one of which is indicated at 172, are arranged to be actuated by power through suitable connections from a continuously rotating fluted shaft 238. This shaft is continuously driven from a motor 32 through suitable driving mechanism, such as that shown in Figure 4. The driving connections for the several type bars are selectively engaged with the fluted shaft by means of key levers 246.

The mechanism for actuating the accumulating devices of the column registers comprises a series of vertically movable toothed differential actuator racks, one of which is indicated at 324, a toothed or fluted shaft 350 continuously driven from the motor 32 for moving the racks upwardly when engaged with the shaft, a differentially operated shaft 320 actuated by the racks during their downward movement through the engagement of the racks respectively with gears 346 fixed to the shaft, and a master wheel 304 for actuating the accumulating devices 300 of a column register 289 connected with the shaft through suitable gearing indicated at 314. The actuator racks 324 are selectively engaged with the fluted shaft 350 upon the actuation of the respective type bar levers of the numeral type bars under certain conditions and are moved upwardly by said shaft to the positions required for their subsequent action. The racks are then disengaged from the fluted shaft and are moved downwardly by a spring pressed bail 332. During their downward movement, the racks are engaged with the respective gears 346 to operate differentially the shaft 320.

The machine shown in said pending application is provided with a space bar mechanism for controlling the escapement and both the type bar mechanism and space bar mechanism operate to cause step-by-step movements of the carriage by letter space intervals. The said machine is also provided with a column tabulator mechanism and with a decimal tabulator mechanism for releasing the escapement to space the carriage greater distances.

All of the mechanisms of the machine briefly described or referred to above have substantially the same construction, arrangement and mode of operation of parts as the corresponding mechanisms illustrated and described in applicant's pending application Serial No. 281,772 and need not further be described herein.

Crossfooter register mechanisms

As shown clearly in Figure 2 of the drawings, the shaft 320 is extended beyond the side plates 239 of the type carriage at each end of said carriage and right and left hand cross-computing

registers or crossfooters 546 and 548 are mounted at the respective ends of the carriage. The totalizer mechanisms of these crossfooters are connected respectively with the ends of said shaft for operation by the shaft. The totalizer mechanisms of the crossfooters preferably are substantially identical and each of these mechanisms has the same general construction arrangement and mode of operation of parts as the corresponding mechanism illustrated and described in the patent to Foothorap, No. 2,145,254, dated January 31, 1939.

The mechanism for driving the totalizer of each crossfooter comprises a master wheel 550 mounted on a shaft 552 to rotate therewith but shiftable longitudinally of the shaft to select the denomination of the totalizer mechanism corresponding with the denomination in which the master wheel 304 is located with relation to the column register. The master wheel 550 is driven by mechanism similar to that shown and described in Foothorap Patent No. 1,847,429, dated March 1, 1932, and in Foothorap Patent No. 2,032,691, dated March 3, 1936. The master wheel shaft 552 is journaled in bearings in the side plates 553 of the crossfooter frame and is driven from the actuator shaft 320 through a gear 554 fixed to said shaft and meshing with a gear 556 journaled on and shiftable axially of the shaft 558 fixed to one of the side plates 553. When the machine is set for addition, the gear 556 is arranged to mesh with a gear 560 secured to the master wheel shaft 552. To set the crossfooter mechanism for subtraction, the gear 556 is shifted axially out of engagement with the gear 560 and into engagement with one section of a twin gear 562. The gear 562 is journaled on a shaft 564 secured to the adjacent side plate 553 and the other section of said gear is constantly in mesh with the gear 560, the gear 562 rotating idly when the machine is set for addition.

The value indicating wheels 566 are journaled on a shaft 568 mounted in the supporting plates 569 of the crossfooter frame and are arranged to be driven in opposite directions respectively, for addition and subtraction by toothed denominational number wheels 570 with which the master wheel 550 is arranged to mesh. The wheels 570 are journaled side by side on the shaft 572 supported in the crossfooter frame plates 569 and said wheels are connected with the value indicating wheels by intermediate gears 574 and 576. The master wheels of the two crossfooter registers are respectively shifted axially step by step to the right, looking at the front of the machine, into engagement successively with the wheels 570 to select the denominations corresponding to the denominations of the column register wheels successively engaged by the master wheel 304 by mechanism described later in this application.

Each crossfooter register is provided with a two-way transfer mechanism of the type illustrated and described in Patents No. 2,032,691 and No. 2,145,254, referred to above. This mechanism includes a series of transfer heads 578, one for each denomination, mounted to rock upon a fixed shaft 580 to either side of a central normal position. Rocking movement of a transfer head is effected initially by the engagement of a wide tooth on the corresponding denominational number wheel 570 with a trip member 582 on the head arranged in the plane of said tooth to rock the head in one direction or the other at the time in the movement of said wheel at which a transfer is required. Movement of the head is con-

tinued in the direction in which it is initially rocked by actuating mechanism including a bell crank actuator lever 584 pivoted at 586 on the frame of the crossfooter, a spring 588 connected with the downwardly extending arm of the lever and urging the forwardly extending arm of the lever toward the axis of the head and a link connection 590 between the head and the latter arm of the actuator lever. The arrangement of each head and its actuating mechanism is such that, in the normal position of the parts, they assume a dead center position providing a toggle lock resisting the action of the spring 588, in which position they are yieldingly held by a pivoted detent 592 urged by a spring 594 against a roller 596 mounted on one end of the link 590. Combined carrying fingers and locking dogs 598 tensioned by springs 600 are mounted on each head and are each provided with a projection 602 arranged in the plane of the next higher denominational number wheel 570 to impart the carrying step of movement to said wheel upon the rocking of the head.

Transfer resetting mechanism for crossfooter registers

After each of the transfer heads 578 is rocked into inclined position in the manner above described, to execute a carry, the head remains in this position until it is positively restored to the normal or upright position shown in Figure 5. The present machine is provided with mechanism which operates, immediately after the master wheel 304 leaves the units of cents position in a column register, to restore automatically the transfer mechanism of the crossfooter or crossfooters which may be then in operation. This mechanism comprises a rod or shaft 604 carried by spaced arms 606 secured to a rock shaft 608 mounted to turn in bearings in the crossfooter frame. In restoring the transfer mechanism, the rock shaft 608 is turned in a counter-clockwise direction (Figure 5) thereby swinging the rod 604 downwardly into engagement with the projecting ends 584^a of the forwardly extending arms of any of the actuator levers 584 which may have been swung upwardly out of normal position by the rocking of a transfer head, thereby swinging said arms of said levers downwardly therewith. This restores the links 590 and the transfer heads to their normal positions shown in Figure 5.

The mechanism for thus actuating the rock shaft 608 comprises an arm 610 secured to the rock shaft, a lever 612 fixed to a rock shaft 614 mounted in bearings 615 on the frame of the carriage and links 616 connecting the arm 610 with the lever 612. The rock shaft 608 is turned in the opposite direction by mechanism comprising an arm 615^a secured to said rock shaft, a lever 617 pivoted at 619 on the frame of the crossfooter mechanism and connected with the arm 615^a by a link 621. The lever 617 is acted upon by a coil spring 623 which constantly tends to swing the same in a counter-clockwise direction (Figure 5) and thereby to turn the rock shaft 608 in a clockwise direction.

The lever 612 is connected by a pitman 618 with a crank pin 620 fixed in a disk 622 journaled on a screw stud 624 threaded into a supporting bar or block 626 secured to one of the side plates of the frame of the carriage, the pitman having a lost motion connection with the lever 612 by means of a stud 628 secured in the lever and engaging in a slot 630 in the pitman. The disk 622 constitutes one element of a one

revolution clutch for actuating the pitman 618 and the arm 612. Pivoted at 630 on the disk is a pawl 632 arranged to engage the teeth of a ratchet wheel 634 journaled on the hub of the disk 622 (see Figure 7). The pawl is acted upon by a leaf spring 638 which tends to swing the pawl into engagement with the teeth of the ratchet wheel 634. A gear wheel 640 is fixed to the hub of the ratchet wheel 634 and is continuously driven by means of a gear wheel 642 secured on an extension on the shaft 238 projecting beyond the adjacent side plate of the carriage.

The pawl 632 is held out of engagement with the ratchet wheel 634 during the movement of the master wheel 304 past the denominational number wheels 300^a of a column register until the master wheel passes from the number wheel of the units of cents position by means of a detent lever 644 pivoted at 646 on a bracket 648 attached to the frame of the carriage, which lever carries a detent stud 650 arranged to engage the tail of the pawl as shown in Figure 5. The lever 644 is acted upon by a coil spring 652 which normally holds the lever yieldingly in position with the stud 650 in engagement with the pawl, the movement of the lever under the action of the spring being limited by means of a stop pin 654. When the master wheel 304 passes from the units of cents position in a register, the lever 644 is swung in a clockwise direction (Figure 9), thereby disengaging the stud 650 from the tail of the pawl 632 to allow the same to be engaged with ratchet wheel 634 by the spring 638. Upon the engagement of the pawl with the ratchet wheel 634, the disk 622 is given a single rotation by said wheel and, during this movement of the disk, the lever 612 is swung downwardly by the pitman 618 thereby actuating the rock shaft 608 and the rod 604 to restore the transfer mechanism. Immediately after the lever 644 is actuated to cause the stud 650 to release the pawl 632, said lever is, itself, released by its actuating mechanism and, when the tail of the pawl has passed the stud, the lever is swung back to normal position by the spring 652 thereby locating the stud in the path of the tail of the pawl. As continued rotation of the disk 622 engages the tail of the pawl with the stud 650, the pawl is again disengaged from the teeth of the ratchet wheel 634, and the disk 622 comes to rest. The usual spring actuated reverse rotation preventing pawl 654^a is pivoted in the crossfooter frame and arranged to engage a notch in the disk 622 to prevent reverse rotation of the disk when the pawl 632 is held out of engagement with the ratchet wheel 634.

The present machine is provided with mechanism for moving the master wheel 550 of each of the crossfooter mechanisms from denomination to denomination along the series of numeral wheels 570 during the passage of the master wheel 304 of the column register actuating mechanism through the several denominations of a column register having the same general construction, arrangement and mode of operation of parts as the corresponding mechanism illustrated and described in Patent No. 2,145,254, and in part in Patent No. 2,032,691, referred to above. Each master wheel 550 is shifted by a master wheel carriage 655 movable on a guide 657 in the direction of the axis of the wheel and connected by a link 659 to a forwardly extending crank arm 661 fixed to the upper end of a vertical rock shaft 663 mounted to turn in

bearings in the crossfooter framework. A rearwardly extending arm 665 is fixed to the lower end of said shaft and is connected by a link 654^b with one of a pair of longitudinally slideable coupling bars 656 and 656^a, one for actuating each of the master wheel carriages. These bars are mounted side by side between a pair of laterally spaced housing plates 658 secured to the frame of the type carriage and said bars slide between upper and lower series of rolls 660. The rock shafts 663 are each acted upon by a coil spring 662 connected, in one crossfooter, with the arm 661 and, in the other crossfooter, with the arm 665 which tends to swing the shaft in a direction to maintain the corresponding carriage 655 in starting position with the master wheel 550 in a position just above the first numeral wheel 570. These springs, acting through the connecting mechanism, urge the coupling bars 656 and 656^a to the left (Figures 8 and 9). A coupling dog 666 is pivoted at 668 upon each of the coupling bars and is acted upon by a coil spring 670 which tends to swing the same upwardly into position to engage and interlock with a lug 672 on the base of each column register. A pin or stud 674 is mounted on each of the coupling dogs 666 and engages in an elongated slot 676 formed in the adjacent housing plate 658, the stud cooperating with cams formed at the opposite ends of the slot to swing the dogs downwardly out of engaging position with relation to the lug 672 on the column register.

Normally the dogs 666 lie in their upper or operative positions, one behind the other as illustrated in Figures 5 and 8, with the pins 674 located in the left hand portions of the corresponding slots 676 and adjacent to the respective cams at the ends of the slots (see Figure 8). When the carriage has advanced the printing point to a position within one letter space of a column position on the work sheet on which a number is to be printed or a position at which the master wheel 304 of the column register actuating mechanism is within one space of the first number wheel 300^a on a column register, the coupling dog or dogs 666 which are in operative position will engage the lug 672 on the column register and will hold the corresponding slide or slides stationary during the continued advance of the carriage. Because of the relative movement of the carriage upon which the crossfooter mechanisms are mounted and the slides 656 and 656^a, the corresponding master wheel or wheels 550 will be advanced from denomination to denomination across the corresponding series of numeral wheels 570. When the master wheel 304 advances one step beyond the lowest denominational order of a column register, the pin on each coupling dog, which is engaged with the lug 672, is engaged by the cam at the right hand end of the corresponding cam slot 676 and the dog is depressed out of engagement with the lug thereby releasing the corresponding coupling slide. Each rock shaft 663 is then swung by the corresponding spring 662 in a direction to carry the master wheel 550 back to its normal or starting position and the corresponding coupling slide is moved back to the left to its starting position shown in Figure 8 with relation to the carriage. Figure 9 shows the coupling slides and associated parts in the positions which they assume when the coupling dogs have disengaged the lug 672 on the column register and the slides have been moved part way back to their starting positions.

The clutch control detent lever 644 is swung in

a clockwise direction (Figures 8 and 9), to throw the one revolution clutch into operation to actuate the resetting mechanism for each of the crossfooters, by the retracting movement of either of 5 the coupling slides, following the release of the coupling dog from the lug 672, under the action of either of the springs 662. The mechanism for swinging the detent lever 644 from the movement of the slides, comprises a connecting lever 678 10 pivoted at 680 on the detent lever 644 and connected by the spring 652 with the bracket 648, this spring normally holding the connecting lever in the position shown in Figures 8 and 9 with relation to the detent lever with a projection 682 15 on the connecting lever in engagement with a stop pin 684 fixed to the detent lever. Thus, with the levers in the relative positions shown in these figures, the spring 652 tends to swing the detent lever 644 in a counter-clockwise direction. To 20 enable the connecting lever 678 to be actuated from the coupling slides, the lever is provided with two downwardly extending projections 686 and 686^a, the projection 686^a being arranged in front of and extending below the projection 686 25 as shown clearly in Figures 5, 8 and 9. The projection 686^a is arranged to be engaged by a connecting pin 688 secured in the slide 656 and extending forwardly therefrom through a slot in the forward housing plate 658. The projection 688 is arranged to be engaged by a connecting pin 688^a fixed in a bar 690 rigidly secured to the slide 656, said pin also extending forwardly from the slide through a slot in the forward housing plate 658. The length of the pin 688^a is such 30 that it does not project forwardly far enough to engage the projection 686^a as shown in Figure 5. In order to enable the projections 686 and 686^a to by-pass the pins 688 and 688^a when the coupling slides are held stationary during the advance of the carriage, each of the projections is 35 provided with a cam face 691 arranged to engage the corresponding pin.

The above described mechanism has the following mode of operation: Referring to the mechanism controlled by the coupling slide 656, when 40 the slide is in its normal left hand position, with relation to the housing plates 658 as shown in Figure 8, the connecting pin 688 is located in the position shown in this figure with relation to the projection 686^a on the connecting lever 678. When the slide is held stationary by the engagement of the coupling dog 666 with the lug 672 on a column register, the cam 691 on the projection 686^a is engaged with the connecting pin 688 by movement of the lever 678 with the carriage and the laterally extending arm of the connecting lever 678 is lifted to allow the pin to pass the projection after which the connecting lever is swung back to its normal position by the spring 652, these movements of the lever being produced 45 without effecting the detent lever 644 which remains in its normal clutch disengaging position. When the coupling slide 656 is released by the action of the coupling dog, and the slide is moved back to the left with relation to the carriage by the slide actuating springs (Figures 8 and 9), the connecting pin 688 engages the right hand side of the projection 686^a thereby swinging the detent lever 644 into the position shown in Figure 50 9 to set in operation the one revolution clutch. During this movement of the detent lever 644 the connecting lever 678 swings as a unit therewith, thereby carrying the projection 686^a upwardly beyond pin 688 and the pin is restored to 55 its normal position shown in Figure 8, by the

movement of the coupling slide. After the pin 688 passes beyond the connecting lever 678, the levers 644 and 678 are restored to their normal positions as shown in Figure 8 by the action of the spring 652 so that the stud 650 on the lever 644 will again engage the tail of the pawl 632 to release the clutch as the disk 622 completes a revolution.

The one revolution clutch is tripped in the same manner by the action of the coupling slide 656^a, the pin 688^a on this slide acting on the connecting lever 678 to swing the detent lever 644 to trip the clutch during the retracting movement of the slide.

The one revolution clutch shown in Figure 5 is arranged to reset the transfer mechanisms of both the crossfooters in the event that the several transfer mechanisms have been operated during the passage of the carriage through the zone of a column register. To this end the rock shaft 614 is extended across the rear of the type carriage and one of the arms or levers 612 is attached to each end of the shaft. Mechanism connected with each of these levers having substantially the same construction as that shown in Figure 5 is provided for restoring the transfer mechanism of each crossfooter. In the present application it has been considered necessary to show this mechanism only as applied to the right hand crossfooter.

It is to be understood that, except as defined in the claims, the invention is not limited to the particular construction and arrangement of parts of the illustrated embodiment of the invention but that the invention may be embodied in other forms within the scope of the claims.

Having explained the nature and object of the invention and having specifically described a construction embodying the invention in its preferred form, what is claimed is:

1. A machine of the class described having, in combination, a frame, a carriage movable in opposite directions across said frame, a register including transfer mechanism, means for restoring the transfer mechanism, a power drive for said means including normally disengaged driving and driven members through which the drive is effected, a movable control member for controlling one of said members to control the drive, a movably mounted pick-up device and an abutment relatively movable to correspond with the relative movement of the frame and the carriage, a dog located on said device to engage said abutment at a predetermined point in the movement of the carriage to hold the dog and abutment from relative movement, means for releasing said dog from engagement with said abutment at another predetermined point in the movement of the carriage, a spring for restoring said device to normal position upon its release, mechanism operated by said device during its return movement for actuating said control member to cause the engagement of said driving and driven members and for then releasing said control member and means for moving said control member, upon its release, into position to disengage the driving and driven members.

2. A machine of the class described having, in combination, a frame, a carriage movable transversely upon the frame, a register including transfer mechanism therefor, means for restoring the transfer mechanism, a power drive for said means including normally disengaged driving and driven members through which the drive is effected, a movable control member for con-

trolling one of said normally disengaged members to control the drive, a movably mounted pick-up device and an abutment relatively movable to correspond with the relative movement of the frame and the carriage, a dog connected with said device and located to engage said abutment at a predetermined point in the movement of the carriage to hold the dog and abutment from relative movement, mechanism for releasing the dog from said abutment at another predetermined point in the movement of the carriage, means movably mounted on the control member through which the control member is actuated, an actuating element on said pick-up device arranged to by-pass said means during the relative movement of the pick-up device and abutment in one direction and to actuate the latter means to operate the control member to cause the engagement of said driving and driven members and then to release said means and the control member during the relative return movement of the pick-up device and abutment and means for moving the control member into normal position to cause the disengagement of said driving and driven members upon its release.

3. A machine of the class described having, in combination, a frame, a carriage movable in opposite directions upon the frame, a register including transfer mechanism therefor, means for restoring the transfer mechanism, a power drive for said means including normally disengaged driving and driven members through which the drive is effected, a movable control member for controlling one of said members to control the drive, a movably mounted pick-up device and an abutment relatively movable to correspond with the relative movement of the frame and the carriage, a dog carried by said device and located to engage said abutment at a predetermined point in the movement of the carriage to hold the dog and abutment from relative movement, an actuating element on said pick-up device, means on said control member constructed and arranged to be by-passed by said element during the relative movement of the pick-up device and abutment in one direction and to be engaged, actuated and then released by said element during the relative return movement of the pick-up device and abutment, first to operate the control member to cause the engagement of said driving and driven members and then to release the control member, means for restoring the control member to normal position upon its release by said element and mechanism engaged by said control member upon its restoration to normal position for disengaging said driving and driven members after a predetermined rotation of the driven member.

4. A machine of the class described having, in combination, a frame, a carriage movable in opposite directions across said frame, a register including transfer mechanism, means for restoring the transfer mechanism, a power drive for said means including normally disengaged driving and driven members through which the drive is effected, a pivoted control lever for controlling the engagement of said driving and driven members, an operating lever pivoted on said control lever, a spring connected with the operating lever and tending to swing said lever in one direction with relation to the control lever, a stop for limiting the movement of the operating lever with relation to the control lever under the action of said spring, an abutment, a pick-up device mounted for movement with relation to the

abutment to correspond with the relative movement of the frame and the carriage, a dog located on said device to engage said abutment at a predetermined point in the movement of the carriage to hold the dog and the abutment from relative movement, means for releasing said dog from engagement with said abutment at another predetermined point in the movement of the carriage, mechanism for restoring said device to normal position upon its release, an actuating element on the pick-up device, a projection on the operating lever constructed and located to

be by-passed by said element during the movement of the pick-up device with relation to the register in one direction and to be engaged, actuated and released by said element to operate and release the operating and control levers during the return movement of said pick-up device to cause the engagement of said driving and driven members and means for restoring said control member to normal position, upon its release, to cause the disengagement of said driving and driven members.

OSCAR J. SUNDSTRAND.
